(57) **CLAIM**

I claim the ornamental design for a beverage can with a portion of a mural, as shown and described.

DESCRIPTION

FIG. 1 is a perspective view of a beverage can with a portion of a mural, showing my new design;

FIG. 2 is a front elevational view of FIG. 1;

FIG. 3 is a rear elevational view of FIG. 1;

FIG. 4 is a top plan view of FIG. 1;

FIG. 5 is a bottom plan view of FIG. 1; and,

FIG. 6 is a bottom perspective view of FIG. 1.

The broken lines showing a mural image and additional beverage cans in FIG. 1 depict environmental matter and form no part of the claimed design.
